Des. 184,776
Patented Mar. 31, 1959

184,776

RADIO FREQUENCY TRANSMITTER APPARATUS

Albert Solomon, Brooklyn, N.Y., assignor to Electronic
Instrument Co., Inc., Long Island City, N.Y., a cor-
poration of New York

Application August 11, 1958, Serial No. 52,152

Term of patent 14 years

(Cl. D26—14)

Fig. 1 is a front perspective view of a radio frequency transmitter apparatus, showing my new design;

Fig. 2 is a top plan view, to a reduced scale; and

Fig. 3 is a side elevational view, to a reduced scale, the opposite side being substantially a mirror image thereof.

I claim:

The ornamental design for a radio frequency transmitter apparatus, substantially as shown and described.
